CLAIM

The ornamental design for engine compartment for agricultural product sprayer, as shown and described.

DESCRIPTION

FIG. 1 is an isometric view of an engine compartment for agricultural product sprayer in accordance with the present invention;

FIG. 2 is a rear elevation view of FIG. 1;

FIG. 3 is first side elevation view of FIG. 1;

FIG. 4 is a second side elevation view of FIG. 1;

FIG. 5 is a top plan view of FIG. 1; and,

FIG. 6 is a front elevation view of FIG. 1.

The broken line showing of various surface features is included for the purpose of illustrating portions of the engine compartment for agricultural product sprayer and forms no part of the claimed design.

1 Claim, 6 Drawing Sheets
